TARPON LURE OR THE LIKE

Mathew A. Strumor, 27 Glenbrook Drive,
New Rochelle, N.Y.

Filed Mar. 17, 1965, Ser. No. 84,313

Term of patent 14 years

(Cl. D31—4)

FIG. 1 is a top plan view of a tarpon lure showing my new design;

FIG. 2 is a side elevational view thereof, the other side being identical;

FIG. 3 is a bottom plan view thereof;

FIG. 4 is a sectional detail view thereof, taken along line 4—4 in FIG. 1; and

FIG. 5 is a front elevational view thereof.

I claim:

The ornamental design for a tarpon lure or the like, as shown and described.
